Primary Examiner — Lilyana Bekic(74) *Attorney, Agent, or Firm* — Mehrman Law Office;
Michael J. Mehrman(57) **CLAIM**

The ornamental design for a metered-dose inhaler, as shown and described.

DESCRIPTION

FIG. 1 is a left side, front, and top perspective view of a metered-dose inhaler showing the new design.

FIG. 2 is a front elevational view thereof.

FIG. 3 is a left side elevational view thereof.

FIG. 4 is a top plan view thereof; and,

FIG. 5 is a bottom plan view thereof.

The broken lines in the drawings depict portions of the metered-dose inhaler that form no part of the claimed design.

1 Claim, 2 Drawing Sheets(56)
